US00D545627S

(12) **United States Design Patent** (10) **Patent No.:** **US D545,627 S**
Chatterton et al. (45) **Date of Patent:** **** Jul. 3, 2007**

(54) **BOWL AND LID**

(75) Inventors: **Chadd R. Chatterton**, Kenosha, WI (US); **Scott D. Brown**, Winthrop Harbor, IL (US)

(73) Assignee: **Pactiv Corporation**, Lake Forest, IL (US)

(**) Term: **14 Years**

(21) Appl. No.: **29/235,770**

(22) Filed: **Aug. 5, 2005**

(51) **LOC (8) Cl.** **07-01**

(52) **U.S. Cl.** **D7/538; D7/602; D7/629**

(58) **Field of Classification Search** **D7/500, D7/509, 524, 533, 538-549, 554.2, 554.4, D7/571, 584, 586, 587, 601-641, 701-708, D7/300, 302, 320, 352, 353, 361, 368, 392, D7/393, 307, 597, 551.2, 553.6, 318, 321, D7/619.1; D9/423-433, 435, 443, 434, 452, D9/761; 206/557; 220/737, 4.23**

See application file for complete search history.

(74) *Attorney, Agent, or Firm*—Baker Botts L.L.P.

(57) **CLAIM**

The ornamental design for a bowl and lid, as shown.

DESCRIPTION

FIG. 1 is a perspective view of a bowl;

FIG. 2 is a top view of the bowl of FIG. 1;

FIG. 3 is side view of the bowl of FIG. 1;

FIG. 4 is a bottom view of the bowl of FIG. 1;

FIG. 5 is a perspective view of the bowl of FIG. 1 with a lid;

FIG. 6 is a top view of the bowl and lid of FIG. 5;

FIG. 7 is a side view of the bowl and lid of FIG. 5, the opposite side view being a mirror image thereof;

FIG. 8 is a front view of the bowl and lid of FIG. 5;

FIG. 9 is a back view of the bowl and lid of FIG. 5; and, FIG. 10 is a bottom view of the bowl and lid of FIG. 5.

The portions shown in phantom lines are not part of the claimed invention, but are included to show environment. The phantom lines illustrate features such as a circular bottom rib and a pull tab rib.

1 Claim, 5 Drawing Sheets
